[57] CLAIM

The ornamental design for a device which is suitable for use in cleaning magnetic heads of magnetic tape recording and/or playback instruments, as shown and described.

DESCRIPTION

FIG. 1 is a side elevational view of a device which is suitable for use in cleaning magnetic heads of magnetic tape recording and/or playback instruments, showing my new design, shown with the cap removed for completeness of disclosure;

FIG. 2 is a side elevational view thereof, shown without the cap and with the cleaning and handle portions in different relative positions;

FIG. 3 is a side elevational view thereof, shown without the cap and with the cleaning and handle portions in different relative positions;

FIG. 4 is a top plan view of the device as shown in FIG. 1;

FIG. 5 is a bottom plan view of the device as shown in FIG. 1;

FIG. 6 is a side elevational view of the device as shown in FIG. 1, but shown with the cap in place;

FIG. 7 is a side elevational view of the device as shown in FIG. 2, but shown with the cap in place;

FIG. 8 is a side elevational view of the device as shown in FIG. 3, but shown with the cap in place.

FIG. 1.

FIG. 2.

FIG. 3.

FIG. 4.

FIG. 5.

FIG. 6.

FIG. 7

FIG. 8.
